US00D550277S

(12) United States Design Patent (10) Patent No.: US D550,277 S
Krause (45) Date of Patent:  Sep. 4, 2007

(54) ALDI SUED TYPE FACE FONT

(75) Inventor: Henning Krause, Berlin (DE)

(73) Assignee: Aldi Einkauf GmbH & Co. oHG,
Mulheim an der Ruhr (DE)

() Term: 14 Years

(21) Appl. No.: 29/254,836

(22) Filed: Feb. 27, 2006

(30) Foreign Application Priority Data

Aug. 29, 2005 (DE) 4 05 04 466

(51) LOC (8) Cl. 18-03

(52) U.S. Cl. D18/24

(58) Field of Classification Search D18/24-31;

See application file for complete search history.
